CALIPER BRAKE ASSEMBLY

John A. Carlson and Theodore M. Tigard, Wichita, Kans.,
assignors to Conchemco, Incorporated, Lenexa, Kans.

Filed Oct. 26, 1972, Ser. No. 301,147

Term of patent 14 years

Int. Cl. D12—11

U.S. Cl. D12—179

FIG. 1 is fragmentary view of a caliper brake assembly showing our new design illustrating the side of the grip and the front of the clamp;

FIG. 2 is a fragmentary top plan view thereof;

FIG. 3 is a fragmentary view thereof illustrating the front of the grip and the side of the clamp;

FIG. 4 is a fragmentary view thereof illustrating the rear of the clamp and the side of the grip opposite to that shown in FIG. 1;

FIG. 5 is a fragmentary view thereof illustrating the rear of the grip and the side of the clamp opposite to that shown in FIG. 3;

FIG. 6 is a fragmentary bottom plan view thereof; and

FIG. 7 is a fragmentary view of a caliper brake assembly showing a second embodiment of our new design illustrating the side of the grip, the sole difference being in the configuration of the grip lever, it being understood that the clamp has been omitted for ease of illustration.

The cable has been broken away in all views to indicate indeterminate length.

We claim:

The ornamental design for a caliper brake assembly, substantially as shown and described.
